(57) CLAIM

The ornamental design for a dentifrice, as shown and described.

DESCRIPTION

FIG. 1 is a perspective view of a segment if the dentifrice of my design;

FIG. 2 is a side elevation view thereof;

FIG. 3 is a end elevation view thereof; and,

FIG. 4 is a top plan view thereof.

The broken line showing of a toothbrush and tube are for illustrative purposes only and form no part of the claimed design.

The dentifrice is at least partially transparent with suspended quadrangular shaped pieces.
